UNITED STATES PATENT OFFICE.

CHARLES SPIRO, OF NEW YORK, N. Y.

TYPE-BAR-SHIFTING MECHANISM.

SPECIFICATION forming part of Letters Patent No. 687,867, dated December 3, 1901.

Original application filed July 27, 1900, Serial No. 25,030. Divided and this application filed October 23, 1900. Serial No. 34,047. (No model.)

To all whom it may concern:

Be it known that I, CHARLES SPIRO, a citizen of the United States, residing at New York, in the county of New York, State of New 5 York, have invented certain new and useful Improvements in Type-Bar-Shifting Mechanism, of which the following is a specification, reference being had therein to the accompanying drawings.

10 This invention relates to type-writers, and particularly to mechanism for shifting and holding the type-bars.

The invention has for its object to provide a novel structure for the support of the type-bars and for shifting said support to bring the upper and lower case characters, respectively, to the printing-point and also to provide means for shifting the type frame or carrier from one position to another to bring 15 into use either upper or lower case characters, and thus temporarily when the said bar-frame is normally in position to present either the upper or lower case character to the printing-point.

20 Other objects and advantages of the invention will hereinafter appear in the following description, and the novel features thereof will be particularly pointed out in the appended claims.

25 In the drawings, Figure 1 is a partial plan of the type-bar frame. Fig. 2 is a vertical transverse section of the same with the adjacent connections and operating devices. Fig. 3 is a side elevation of said frame and of the devices for shifting the same. Fig. 4 is an elevation of the throw-plate. Fig. 5 is a similar view of an operating-lever therefor. Fig. 30 6 is an elevation of the connecting-plate for a key-lever. Fig. 7 is a front elevation of the parts shown in Fig. 3. Fig. 8 is a perspective of the shifting-lever with a portion of its spring. Fig. 9 is an enlarged elevation of the shifting-lever and coöperating parts in an intermediate position, and Fig. 10 is a detail 35 elevation of the shifting devices shown in Fig. 3 with the parts shown by dotted lines when the spring is shifted by the lever.

40 Like letters of reference indicate like parts throughout the several figures of the drawings.

This application is a division of my origi-

nal application, filed July 27, 1900, Serial No. 25,030, and relates to the type-bar shifting and holding mechanisms primarily. For this reason the carriage and auxiliary parts have 55 not been illustrated, as the invention is capable of use with any desired form of coöperating mechanisms constituting a complete machine.

Referring to Figs. 1 to 7, inclusive, a description of the type-bar frame and its support and operation will now be given. O represents said frame, and it comprises an upper substantially cylindrical portion O', having any suitable or desirable type-bar brackets 60 O², secured by screws O³ in any usual or desired manner. Depending at each side of this circular upper portion are legs O⁴, which extend to the base portion of the frame A and are thereto pivoted, as at O⁵. The frame 65 A at its top is of such dimension at the opening for receiving the type-bar frame as to permit its oscillation on its pivots for the purpose of bringing into use either the upper or the lower case type on each of the bars 70 75 of the series employed. The type-bars P are each mounted in the brackets in the usual manner and carry each an upper and lower case type, as is usual. A buffer-ring Q is supported in any suitable manner—as, for example, by brackets Q' from the bar-frame O—while the ligaments P' of the type-bars are adjustably connected with straps P² by means of nuts P³ in the usual manner, and each of said straps is pivotally connected at P⁴ with 80 85 its key-lever, the pivot P⁴ being substantially in the same vertical plane as the pivots O⁵ of the bar-frame.

It is proper to state that it is not essential to the satisfactory operation of my invention 90 that the pivotal connection of the type-bar ligaments and of the type-bar frame should be in exactly the same plane. In fact, they may be in entirely different planes; but in order to make the touch of the keyboard as 95 light as possible it is better to have the line of draft in the ligament and straps to the type-bar as near direct as possible, and, furthermore, in order that any depression on a key of the keyboard shall not have a tendency 100 to shift the bar-frame unintentionally it is preferred that the pivots of the ligaments and

of the bar-frame should be in substantially the same vertical plane. The pivotal support of the bar-frame at a low point in the machine is a matter of importance in that it 5 reduces to a minimum the amount of movement at the pivot of the frame to produce the extent of movement required at the printing-point. This movement is indicated by the dotted lines R R' in Figs. 2 and 3, the former 10 being the position of the bar-frame in printing one character in either upper or lower case and the latter line R' being the position of the frame when said character is not in use. It is apparent upon an inspection of 15 these lines that the distance through which it is required to move the bar-carrier to produce a change in the printing characters is extremely limited even at or adjacent to the printing-point, where the greatest movement 20 occurs. The dotted line R' of Figs. 2 and 3 represents the space provided in the upper portion of the frame A for the purpose of this movement of the type-bar frame.

It now remains to describe the devices employed for shifting the bar-frame from upper 25 to lower case, and vice versa.

Referring to Figs. 3 to 7, O⁶ is a pin projecting from the side of the bar-frame O. S is a bracket extending downwardly from the 30 frame A and carrying a pivot S'. On this pivot is supported a throw-plate S², which is perforated at S³, Fig. 4, for the reception of the pivot. The upper end of the throw-plate is slotted, as at S⁴, to embrace the pin O⁶ of the bar-frame. 35 Below the pivot-hole S³ the plate S² carries pins S⁵ and S⁶, which are disposed at each side of the pivotal point of the plate and below said point. Upon the same pivot S' and in front of the throw-plate S², as seen in Fig. 3, there is 40 mounted a lever T by means of the perforation T' in said lever. This lever is formed with a projection T², a pin T³, and a depending arm T⁴, having an angular extension T⁵ for the purpose of connecting said lever with 45 the frame of the machine by means of a spring T⁶, (see Fig. 7,) secured to the frame A at a point over and in the same vertical plane as the pivot S'. U represents a connecting-plate adapted to be mounted on the 50 headed pin T³ of the lever T, and at its lower end said plate is perforated, as at U', for connection at U³ with a key-bar U², pivoted at U⁴ to the base portion of the frame A. The plate U is recessed at U⁴ to allow movement 55 of the extension T⁵ of the lever T, which travels within said recess to shift the spring T⁶. A vertical slot U⁸ is formed in plate U, which slot embraces the shank of headed pin T³ of lever T and is of such length as to permit of 60 vertical movement of plate U through the medium of shifting-key U². The upper portion of the plate U is formed with a head U⁵, having projections U⁶ and U⁷ at different points in its length, which coact with the pins S⁵ and S⁶, respectively, of the throw-plate S when the key U² is employed to shift the bar-frame, as will now be described. Taking the

parts in the position shown in Fig. 3, with the projection U⁶ over the pin S⁵ and with the throw-plate embracing the pin O⁶ in the position shown in full lines, which is that occupied by it when the type-bar frame is toward the front of the machine and when, for example, lower-case type are in use, a depression of the key-bar U² draws downwardly on 70 the plate U, which by its projection U⁶, bearing upon the pin S⁵ at the left of the pivot of the throw-plate S², oscillates said plate on said pivot and brings the pin O⁶ and bar-frame to the position shown in dotted lines, 80 the normal position of pin O⁶ with relation to the pivot S' being indicated by dotted line x and the assumed position by this depression of the key-lever being the dotted line y. During this operation the pin S⁵ bears downwardly on projection T² of the lever T, causing said lever to oscillate on the pivot S' and carry the lower end of the spring T⁶ to a point below, but still at the same side of said pivot, whereby the spring tension returns the parts 90 to their original position when pressure is removed from the key-bar U². When the parts are controlled by the lever T, the lower end of the spring T⁶ is thrown to the opposite side of the pivot S' to shift the tension of the 95 spring. Now it will be noted that in this action the spring T⁶, extending from extension T⁵ of lever T to the frame A, always lies in a line passing at the left of pivot S', on which lever T is mounted, and is exerting 100 a tension on the lever T which tends to keep it in the position shown in full lines—that is to say, to keep the projection U⁶ of plate U over the pin S⁵ of the throw-plate—so that upon removing pressure from the key-lever 105 U² the parts will resume the position which they held before said lever was depressed. In this manner by the use of the key U² and without operating the lever T by hand the type-bar frame may be oscillated while printing the lower-case to bring upper-case letters to the printing-point intermittently, as in the ordinary use of the machine. Now if it be desired to use upper-case letters exclusively, then by raising the lever T to 110 the position indicated in dotted lines in Fig. 10 the pin T³ carries plate U to the right until the lever strikes against pin S⁶ and moves the throw-plate on pivot S' so that the upper slotted end of the throw-plate takes 115 the position indicated by the dotted line y, which is the same as in Fig. 3, thus bringing upper-case letters into use and at the same time shifting spring T⁶ to the right of pivot S'. This shifting of the plate U brings its 120 projection U⁷ over pin S⁶ of the throw-plate S, which now lies in a higher horizontal plane than before, and the spring T⁶ will extend at the right of the pivot S' of the lever and will maintain projection U⁷ over pin S⁶, so that 125 the bar-frame, thus being in position to present upper-case letters normally at the printing-point, may, as before and solely by the use of the key-bar U², be shifted to bring into 130

action at will and intermittently the lower-case printing characters. It will be seen, therefore, that with the bar-frame in position to present normally either upper or lower case characters to the printing-point a change of printing characters can be accomplished at the keyboard without manipulating a special device, such as the lever T. When the bar-frame is shifted to the right by lever T, the projection T² contacts with pin S⁵ of the throw-plate; but when shifted to the left lever T contacts with pin S⁶ for a similar purpose. The slot U⁸ of plate U permits such a vertical movement of plate U as is necessary when key U² is depressed to act upon either of the pins S⁵ S⁶ to operate the throw-plate. At such times the spring T⁶ holds pin T⁸ in position on one or the other side of a line passing vertically through pivot S', the spring taking a position on one or the other side of pivot S'. Furthermore, it is apparent, as shown in Figs. 4, 5, and 6, that each of the elements employed in this mechanical structure of bar-frame-shifting mechanism is such as can be readily struck up from sheet metal, closely and concisely assembled, and accurately and satisfactorily operated, whereby not only a minimum of cost of manufacture, but practical utility and serviceability exist.

30 It is apparent that many of the details of construction herein shown and described may be varied to a great extent by the exercise of such mere mechanical skill as is possessed by persons conversant in the construction and operation of machines of this character.

It is well known in the art that the "touch" of a keyboard is materially affected by the friction and weight of the parts that are actuated by a key, and these elements must be reduced to a minimum. This object is accomplished by rigidly-connected supports for the type-bar frame, which are diametrical, require only two points of support, and those pivotal in their nature. Furthermore, the points of support are in a vertical plane passing through the center of the type-bar frame and substantially the center of the platen, so that the weight and bulk of the parts of the bar-frame on opposite sides of this center balance each other, and thus further contribute materially to lightening the touch.

Having described my invention, what I claim as new, and desire to secure by Letters Patent, is—

55 1. In a type-writer, a machine-frame, an annular type-bar frame having rigid supports pivoted on a line passing through a vertical plane at the center of said bar-frame for oscillation within the frame of the machine; substantially as specified.

2. A type-bar frame comprising an upper annular portion and rigidly-connected side portions extending to a point below the annular portion, and pivoting means upon the

65 lower side portions on a line passing through a vertical plane at the center of said annular portion; substantially as specified.

3. In a type-writer, a machine-frame, an oscillating type-bar frame pivoted at its lower portion in the base of said machine-frame at a point substantially in the central vertical plane of the type-bar frame; substantially as specified.

4. In a type-writer, a machine-frame, a type-bar frame comprising an upper annular portion adapted to receive and carry type-bar brackets, integral side portions extending downwardly and pivoted to the machine-frame at the base thereof on a line passing through a vertical plane at the center of said annular portion; substantially as specified.

5. The combination with a type-writer frame, of an oscillating type-bar frame pivoted at opposite sides on a line passing through a vertical plane at substantially its center; substantially as specified.

6. In a type-writer, a machine-frame, a type-bar frame pivoted at the base of the machine-frame and substantially in a vertical plane passing through the center of said bar-frame, type-bars carried by said bar-frame, key-bars mounted in said machine-frame, and ligaments for said type-bars connected with said key-bars in the same vertical plane with the pivot of the type-bar frame; substantially as specified.

7. In a type-writer, a machine-frame, a platen supported at the upper portion thereof, a type-bar frame comprising an upper annular portion having opposite rigidly-connected side portions depending to form a pivotal support for the type-bar frame in a vertical plane passing through substantially the center of the platen, type-bar brackets, type-bars, and a buffer for the same carried by said bar-frame; substantially as specified.

8. In a type-writer, an oscillating type-bar frame having a pivotal support at its lower portion substantially in a vertical plane passing through the center of the bar-frame, type-bars supported by said frame, key-bars mounted independent of said frame, and pivotal connections from said type-bars to said key-bars in a vertical plane passing through the center of the bar-frame; substantially as specified.

9. In a type-writer, a pivotally-supported annular type-bar frame, type-bars with a plurality of printing characters on each, a platen, and means for oscillating the type-bar frame to bring different characters to the printing-point; substantially as specified.

10. A pivotally-supported annular type-bar frame, and means for oscillating the same on its pivots; substantially as specified.

11. In a type-writer, a pivoted annular oscillating type-bar carrier, and means for shifting the same into or out of either of its operative positions through the instrumentality of a key at the keyboard; substantially as specified.

12. In a type-writer, a pivotally-supported type-bar frame having a projection, a throw-plate supported from the frame of the ma-

chine and connected with said projection, and means for operating the throw-plate to shift the type-bar frame; substantially as specified.

5 13. A pivoted type-bar frame having a pin, a throw-plate embracing said pin supported pivotally from the frame of the machine and having a pin below and at each side of its pivotal support, and means for operating the

10 throw-plate through the instrumentality of either of said pins; substantially as specified.

14. A pivoted type-bar frame, a throw-plate for the same having oppositely-located pins, a lever having a pin moving in an arc below

15 the pins of the throw-plate, a connecting member extending from a key-lever to the pin of the said lever and having a head with projections to operate with the pins of the throw-plate; substantially as specified.

20 15. As a means for shifting the type-bar carrier of a type-writer, a throw-plate and a lever, both of which are mounted on a common pivot, the throw-plate having a pin at each side of and below the pivot, a lever hav-

25 ing a projection and a pin, a connecting-plate having a head with projections for operating in conjunction with each pin of the throw-plate, and a spring extending from the lever to the frame of the machine; substantially

30 as specified.

16. As a means for shifting the type-bar frame of a type-writer, a throw-plate connected with the frame, supported from the type-writer frame and having a pin at each

side of and below its support, a lever pivoted 35 to the support of the throw-plate and having a pin and an arm, a spring connecting the lever with the machine-frame, a key-lever, and a connecting-plate having an opening for the operation of the arm of the lever and for connection with the pin of said lever and having a projection to coöperate with each of the pins of the throw-plate; substantially as specified.

40 17. A throw-plate for a type-bar-frame- 45 shifting mechanism having a bifurcated upper end, a pivot-opening, and a pin below and at each side of said opening; substantially as specified.

45 18. A lever for a type-bar-frame-shifting 50 mechanism having a projection, an opening for its pivotal support, a pin below said opening, and a projecting arm below the pin for the connection of a spring; substantially as specified.

55 19. A connecting-plate for type-bar-frame-shifting mechanism comprising a head having projections, an extension for connection with a key-lever, and an intermediate opening for the reception of a lever and its pin; 60 substantially as specified.

In testimony whereof I affix my signature in presence of two witnesses.
